UNITED STATES PATENT OFFICE.

AUSTIN BOND, OF LISCARD, ENGLAND.

MEAT-HOLDER FOR SLICING-MACHINES.

1,147,923.

Specification of Letters Patent. Patented July 27, 1915.

Application filed November 25, 1912. Serial No. 733,525.

To all whom it may concern:

Be it known that I, AUSTIN BOND, a subject of the King of Great Britain, residing at Liscard, in the county of Chester, in the 5 Kingdom of England, have invented certain new and useful Improvements in Meat-Holders for Slicing-Machines, of which the following is a specification.

This invention relates to a machine for 10 slicing bacon, bread and other substances, the object being to produce a simple machine, cheap in manufacture, and that shall be capable of being worked and fed by hand.

The invention is best described by aid of 15 the accompanying drawings, in which:—

Figure 1 is an elevation of the machine from the side at which the feed table is located; Fig. 2, a plan view of the machine; Fig. 3, a vertical section on the lines Z Z 20 of Figs. 1 and 2; Fig. 4 is a rear view of an accessory part which is shown in position on the feed table in Fig. 2; Figs. 5 and 6 are a side view and a section respectively of the feeding device. Fig. 7 is a plan view of 25 the machine in which the knife is mounted at a slight angle to the gage plate.

The machine is of the type in which a rotary disk knife is employed for cutting the material as it is reciprocated toward and 30 away from the knife, and is fed forward toward the knife after the cutting of each slice.

a is a rotary disk knife supported by means of a standard b.

35 c is a bedplate to which the standard b is attached.

d, Figs. 2 and 3 is a metal angle piece attached to the bedplate, whereby it can be clamped to a table or the like.

40 e is a shaft carrying a crank f mounted on standard b.

f is a crank carrying an operating handle g, and mounted on shaft e preferably by being screwed on the threaded end e' of said 45 shaft e.

h is a gear wheel keyed on to this shaft. This gear wheel is housed in a recess in standard b.

i is a pinion gearing into gear wheel h.

50 The gear wheel i is firmly attached in any convenient manner to the knife a preferably by small screws j, Fig. 1. This pinion i is annular, and is seated on a boss k on standard b and serves as an axle for the support 55 of the knife a.

l is a central disk, also attached to the

knife a, and the pinion i by the aforesaid screws j.

m is a screw retaining the disk l and screwed into a threaded opening in disk k. 60 It thus holds the knife a and pinion i firmly in position on the boss k, but by undoing this screw, these parts can be pulled off. The disk l turns freely about the head of the screw m when the screw m is screwed up 65 tight.

It will be seen from Figs. 1 and 3 that the gear wheels h and i are such as to impart to the knife a a velocity of rotation considerably higher than that imparted to the 70 shaft e.

A flange n is formed on the upper part of standard b and extends over the edge of the disk knife a, and serves as a guard for its 75 edge.

o is an adjustable plate forming a continuation of the flange n. This plate is hinged to the standard b at the point o' and is provided with a spring o², Fig. 3, which normally keeps the plate down to its working 80 position, but when the plate is forcibly thrown back and has passed the neutral point, it holds the plate in the thrown back position, and has the advantage of then taking up less room on the counter. 85

q, Figs. 1 and 2, is a vertical plate, which serves both as a guard and as a gage piece to determine the thickness of the slice. r is a foundation flange formed in one with the 90 vertical plate. This works between guides s s' on the bedplate. These are preferably sloping, and one of them s' is provided with a scale to one-sixteenth of an inch or millimeter or other small divisions. The flange r is provided with a pointer t, which co-operates with the scale on the guide s'. u is a bolt mounted in the bedplate c, and having 95 a winged nut v and washer w. It will be seen from Fig. 1 that the vertical plate q extends up to the neighborhood of the edge of the knife a so as to support the material while it is being cut, while permitting the slice to fall away on to the base plate c beyond the knife a, when it is cut. The bedplate c preferably extends only to a line 100 near the knife a. x is a second plate or feed table hinged to the base plate c along this line. This feed table preferably has its upper surface polished so that the material to be cut can be easily pushed backward and forward over the surface. y y are 105 three rollers mounted in or on the feed table

110

α to enable the operator to more easily move the bacon or other material to and fro.

In Fig. 4 is shown a spring catch for holding the feed table in its folded position, 5 suitable for transport. The catch at one end is hinged to the bedplate by a screw as shown. At the other end it has a slot 2 having a lateral extension at its upper end. 10 3 is a screw fixed in the bedplate c , and working in the slot 2. 4 is a spring fixed to the plate 1 at the handle peg 5, and bearing against the shank of screw 3. This spring normally keeps the pin in the little embayment at the top of the slot 2 as shown, 15 but if by means of the handle pin 5 the bottom of the blade 1 is raised until the pin 3 arrives at the parallel portion of the slot 2, the bedplate α at once can be brought down parallel with c .

20 Figs. 5 and 6 show the feeding device which is worked entirely by hand. In these 7 is a box having a series of pin holes through which pins 8 project. 9 is an internal box carrying pins 8. This box is sup- 25 plied with a handle 10. A spring pin 11 is arranged on the top of the box 7 so as to en- gage in perforations in the box 9 for the 30 purpose of locking them, together, either when the pins 8 project or are in the with- drawn position. This pin is attached to a spring 12 fixed at its opposite end to the box 7.

The mode of action is as follows: The two bedplates being in line, a piece of bacon is 35 placed on bedplate α . If a three-sixteenth cut has to be made, the pointer t is put on the line between 2 and 4 on the scale s' . The 40 implement shown in Figs. 5 and 6 is now pressed against the bacon pressing it in turn against the plate g until the spikes 8 enter the bacon. The handle g is now rotated, and the bacon holder is reciprocated in a 45 line parallel with the knife. A slice is thus cut off, and the knife being preferably sloping slightly causes the slice to fall away

slightly so that it does not drag on the knife. The bacon is reciprocated back and again pressed against the plate g and pushed forward again, and so on until the last cut possible is made without the knife 50 coming in contact with the pins 8. The bacon holder is now taken off. The pin 11 lifted, and the two boxes drawn apart, when the last slice of bacon falls off, the two boxes are again placed together, the pin 11 55 allowed to fly back into position, and the device is ready for affixing another piece of bacon.

I declare that what I claim is:—

In a cutting machine of the class de- 60 scribed, a holder comprising an outer box portion, an internal box portion positioned within said outer box portion, a handle car- ried by said internal box portion, said outer box portion provided with a plurality of en- 65 larged apertures, said internal box portion provided with a plurality of spurs passing through said enlarged apertures, a spring latch pivotally secured to said outer box portion, said inner box portion provided 70 with a plurality of apertures, said spring latch provided with a projecting pin adapted to fit in one of said apertures formed in said inner box portion for holding said inner box portion in a set position relative to 75 said outer box portion, and said inner box portion adapted to be drawn within said outer box portion for withdrawing said spurs within said apertures whereby an ar- 80 ticle gripped by said spurs will be readily disengaged from said spurs.

In witness whereof, I have hereunto signed my name this 13th day of November 1912, in the presence of two subscribing wit- nesses.

AUSTIN BOND.
